[57] CLAIM

The ornamental design for an extendable computer storage desk, as shown and described.

DESCRIPTION

FIG. 1 is a perspective view of an extendable computer storage desk showing our new design;

FIG. 2 is a perspective view of the desk in extended position;

FIG. 3 is a perspective view of an alternate embodiment of the desk shown in FIG. 2; the other views of the desk in closed position are substantially similar to those of FIGS. 4-9 but with the keyhole on the left side;

FIG. 4 is a right side elevational view of FIG. 1;

FIG. 5 is a left side elevational view of FIG. 1;

FIG. 6 is a top plan view thereof;

FIG. 7 is a bottom plan view thereof;

FIG. 8 is a front elevational view thereof; and

FIG. 9 is a rear elevational view thereof.
